DIGITAL CLOCK

Nobuyoshi Hirosawa, Nagano-ken, Japan, assignor to
Kabushiki Kaisha Sankyo Seiki Seisakusho, Shimosuwa-
machi, Suwa-gun, Nagano-ken, Japan

Filed June 13, 1973, Ser. No. 369,611

Claims priority, application Japan Apr. 24, 1973

Term of patent 14 years

Int. Cl. D10—01

U.S. Cl. D10—15

Fig. 1

Fig. 2

Fig. 3

Fig. 4

FIG. 1 is a front elevational view of a digital clock showing my new design;

FIG. 2 is a left, side-elevational view thereof;

FIG. 3 is a right side, top and front perspective view thereof; and

FIG. 4 is a left side, front and bottom perspective view thereof.

The rear of the clock, not shown, is substantially plain and unornamented, except for the alarm lever.

I claim:

The ornamental design for a digital clock, as shown and described.
